CLAIM

The ornamental design for an exercise mat with foot positions, as shown and described.

DESCRIPTION

FIG. 1 is a top view of an ornamental design for an exercise mat with foot positions;

FIG. 2 is a bottom view of the exercise mat;

FIG. 3 is a front side view of the exercise mat;

FIG. 4 is a back side view of the exercise mat;

FIG. 5 is a left side view of the exercise mat; and,

FIG. 6 is a right side view of the exercise mat.

The broken lines representing the edges of the exercise mat form no part of the claimed design.

1 Claim, 3 Drawing Sheets
